UNITED STATES PATENT OFFICE.

HAROLD G. WARR, OF PARK RIDGE, ILLINOIS, ASSIGNOR TO THE P & M COMPANY, OF CHICAGO, ILLINOIS, A CORPORATION OF ILLINOIS.

RAIL ANCHOR.

Application filed January 13, 1926. Serial No. 80,981.

My invention relates to rail anchoring devices for resisting the longitudinal creeping movement of railroad rails.

The primary object of the invention is to provide a new and improved one-piece rail anchor device which will be relatively inexpensive to manufacture, which will be easy of application to a rail, and which will maintain a firm grip on the base flange of a rail when in its applied position thereon.

A more specific object is to provide an improved one-piece rail anchor formed with jaw portions adapted to grip the top and bottom surfaces of a rail base at one side of the rail and formed with means for engaging the top and vertical surfaces of said base flange at the other side of the rail to lock the anchor in its applied position.

Another object is to provide a one-piece device which may be conveniently made from a flat metal plate recessed to provide the rail-gripping jaw portions of the device, the said jaws being so disposed with relation to each other as to provide in effect a relatively wide bearing surface with respect to the thickness of the plate from which the device is made.

The invention has for further objects the provision of such other new and improved features of construction and arrangement of parts as will be hereinafter described and claimed for carrying out the above stated objects and such other objects as will appear from the following description of a preferred embodiment of the invention.

A preferred embodiment of the invention is illustrated in the accompanying drawing, wherein—

Fig. 1 is a plan view of the base portion of a railroad rail showing a rail anchoring device, constructed in accordance with my invention, applied thereto.

Fig. 2 is a side elevation of the rail anchor device, the base portion of the railroad rail being shown in section.

Fig. 3 is an end view of the device shown in Fig. 2, the said view being taken from the left of Fig. 2, and

Fig. 4 is a view in perspective of the rail anchor device shown in the preceding figures.

In the drawing, the numeral 10 designates the base portion of a railroad rail and the numeral 11 designates one of the cross ties on which the rail is supported.

The embodiment of the invention shown

in the drawing consists of a rail base embracing yoke cut from a steel plate and bent to the configuration shown in the drawing. The yoke consists of a body portion 12 which extends across beneath the rail base and is formed with hook shaped jaw portions 13 and 14. The jaw portion 13 comprises a relatively long arm 15 bent to a U-shaped configuration to provide spaced jaws 13^a—13^b. The arm 15 is formed from the material of the blank which is ordinarily cut away to provide the recess for the base of the rail. However, in this embodiment, the arm 15 is made relatively long, as shown in dotted lines in Fig. 4, and is bent outwardly toward the end of the yoke to form said U-shaped configuration. The lower edges of the spaced jaws are tapered to correspond with the inclination of the rail base so as to bear flat against said inclined top surface of the rail base when the anchor is applied thereto. The free end of the jaw portion 13^b is formed with a depending shoulder 16 adapted to snap into engagement with the vertical surface 17 of the rail base when the anchor is forced to its applied position on the rail.

The jaw end 14 of the anchor is formed with a jaw 14^a. The portion of the recess 18 underlying the jaw 14^a conforms to the configuration of the rail base so that the lower edge of this jaw and the upper edge of the body have a snug fit on the rail and are driven into wedging engagement with the upper and lower surfaces of the rail base when the anchor is moved from the dotted line position of Fig. 2 to the full line position. The upper edge of the body portion at the jaw end 14 of the anchor bears against the bottom surface of the rail base to substantially the middle of said base, at which point it inclines downwardly with respect to the rail base, as shown at 19, so that a portion of the recess 18 underlying the spaced jaws will be somewhat wider than the thickness of the rail base. This construction permits the spaced jaws to be readily hooked over one base flange of the rail, and provides a pivot point 20, about which the anchor rocks when it is applied.

In order to provide the necessary clearance to permit the jaw 14^a to clear the opposite edge of the rail base, the recess is made somewhat longer than the width of the base flange of the rail, whereby the an-

chor may be applied to its initial position by hooking the spaced jaws over one edge of the rail base, as shown in dotted lines in Fig. 2, and then shifting the anchor transversely of the rail until the jaw 14^a clears the opposite edge of the rail base.

The jaw 14^a is preferably disposed at an angle to the body 12. The desired angularity of this jaw may be effected by bending it from either side of the body. In the drawing, the said jaw is bent outwardly from the body in the same general direction as the long arm 15, whereby a line parallel with the body passing through the end of the jaw 14^a will pass between the said spaced jaws 13^a and 13^b at the opposite side of the rail.

In applying the anchor to a rail, the spaced jaws 13^a—13^b are first hooked over one flange of the rail base so that shoulder 16 will engage the upper surface of the rail base, substantially as shown in Fig. 2 of the drawing. With the anchor in this preliminary position, the end of jaw 14^a will clear the opposite edge of the rail base and the apex 20 of the angle formed by the edges 19 and 21 of the body will be a short distance to the left of the center of the rail base, as viewed in Fig. 2. The anchor is then driven transversely of the rail to force the jaw 14^a upon the inclined upper surface of the rail base. This movement of the jaw 14^a upon the rail rocks the anchor about the pivot point 20. This rocking movement is permitted without subjecting the anchor to any substantial stress by reason of the fact that the pivot point 20 is substantially midway between the jaws at opposite ends of the anchor. Under such condition, the spaced jaws 13^a—13^b move down the inclined surface of the rail base the same vertical distance that the jaw 14 moves upwardly on the inclined surface of the flange at the opposite side of the rail. There is, however, some preliminary tension effected by reason of the engagement of the shoulder 16 with the top surface of the rail base. The degree of this preliminary tension is determined by the length of the shoulder 16 and may be partially or entirely relieved when the shoulder snaps down over the edge of the rail base to lock the anchor in its applied position. Preferably, the said shoulder is of such length that a slight tension remains in the jaw 13^b after the anchor has been driven home. The main grip of the anchor, however, is obtained by reason of the wedging engagement of the jaw 14^a and the surface 21 of the body with the upper and lower surfaces, respectively, of the rail base.

In the drawing I have shown a structure that is particularly suitable to be made of metal of low grade, since any substantial spring tension is not essential to the proper

operation of the device. However, it will be apparent that in situations in which it may be desirable to use a higher grade metal having more resiliency, advantage of such resiliency can be obtained by shifting the pivot 20 toward the jaw 14^a or by increasing the angularity of jaw 14^a with respect to the upper inclined surface of the rail base so as to provide a differential arrangement of parts which will effect an increasing spring grip as the anchor is driven home. It will also be seen that the preliminary spring grip of the anchor may be increased by decreasing the vertical distance between the bearing surfaces of the jaws 13^a—13^b and the horizontal edge 21 of the anchor body. By such construction the anchor may be subjected to greater distortion than will be relieved by the movement of the jaws 13^a, 13^b downwardly on the inclined surface of the rail base.

While I have described my invention in connection with one specific embodiment it will be obvious that modifications in structure may be made without departure from the spirit of my invention. I, therefore, wish it understood that I contemplate all variations in structure that come within the scope of the appended claims.

I claim:

1. A rail anchor comprising a yoke which is relatively thin with respect to its vertical dimension when applied to a rail, formed at one end with a jaw portion for gripping the top and bottom surfaces of a rail base at one side of the rail, provided at the other end with a jaw portion normally engaging the top surface of the rail base at the other side of the rail, and provided with means for engaging the vertical edge of the rail to lock the anchor in its applied position.

2. A rail anchor adapted to be driven transversely of a rail to its applied position comprising a yoke which is relatively thin with respect to its vertical dimension when applied to a rail, formed at one end with a jaw portion for gripping the top and bottom surfaces of a rail base at one side of the rail and provided at the other end with a jaw adapted to bear against the top and vertical surfaces of the rail base to lock the anchor in its applied position.

3. A rail anchor comprising a yoke which is relatively thin with respect to its vertical dimension when applied to a rail, formed at one end with a jaw portion for gripping the top and bottom surfaces of a rail base at one side of the rail and provided at the other end with a jaw adapted to bear against the top and vertical surfaces of the rail base to lock the anchor in its applied position; the position of said jaw with respect to the body being such that the said jaw is tensioned during its application to its normal operative position.

4. A rail anchor comprising a yoke which is relatively thin with respect to its vertical dimension when applied to a rail, formed at one end with a relatively rigid 55 jaw portion adapted to be driven transversely of the rail into wedging engagement with the top and bottom surfaces of a rail base at one side of a rail and formed at the other end with a resilient jaw adapted to bear 10 upon the top surface of the rail base; the position of said resilient jaw with respect to the body of the anchor being such that the said jaw is tensioned by transverse movement of the yoke to its applied position.
- 15 5. A rail anchor comprising a steel plate recessed to provide a yoke having at one end a relatively rigid jaw portion adapted to be driven transversely of the rail into wedging engagement with the top and bottom surfaces 20 of a rail base at one side of a rail and having at the other end a resilient jaw adapted to bear upon the top surface of the rail base; the position of the said resilient jaw with respect to the body of the anchor 25 being such that the said jaw is tensioned by the transverse movement of the yoke to its applied position.

6. A rail anchor comprising a yoke member formed at one end with a jaw adapted 30 to be hooked over one edge of a rail base and provided at the other end with a jaw portion adapted to grip the top and bottom surfaces of said base at the opposite side of the rail; the part of said last mentioned jaw 35 portion for gripping the top surface of said base being disposed at an angle with respect to the side faces of the yoke.

7. A rail anchor comprising a yoke formed at one end with a jaw portion adapted 40 to be driven into gripping engagement with the top and bottom surfaces of a rail base at one side of the rail, and formed at the other end with spaced jaws adapted to be moved transversely of the rail into gripping engagement with the top surfaces of the rail base at the opposite side of the rail; the spaced jaws being so disposed with relation 45 to the first mentioned jaw as to assume their operative position when said first mentioned jaw is driven home.

8. A rail anchor comprising a yoke formed at one end with a jaw portion adapted to be driven into gripping engagement with the top and bottom surfaces of 55 a rail base at one side of the rail, and formed at the other end with spaced jaws for engaging the top surface of the rail base at the opposite side of the rail; one of said jaws being provided with a shoulder adapted to snap down over the upper longitudinal edge of the rail base when the yoke is driven home.

9. A rail anchor comprising a metal plate recessed to provide a long lug at one end 60 and a short lug at the other, adapted to

bear against the top surface of the rail base at opposite sides of the rail; said long lug being bent to provide rail engaging jaws spaced from each other longitudinally of the rail.

10. A rail anchor comprising a metal plate recessed to provide long and short lugs at opposite ends of the plate adapted to bear against the top surface of the rail base at opposite sides of the rail; said long lug being bent to provide rail engaging jaws spaced from each other longitudinally of the rail and the free end of one of the spaced jaws being formed with a shoulder 70 for engaging the vertical surface of the rail base.

11. A rail anchor adapted to be driven transversely of a rail to its applied position comprising a yoke member formed at one end with spaced jaws for engaging the top surface of a rail base at one side of the rail, and at the other end with a jaw for engaging the top surface of the base at the other side of the rail; the upper edge of the body of the yoke intermediate said jaws 80 being formed at an angle, one leg of which bears against the bottom of the rail base when the anchor is in its applied position.

12. A rail anchor adapted to be driven transversely of the rail to its applied position, comprising a yoke member formed at one end with spaced jaws for engaging the top surface of the rail base at one side of a rail, and at the other end with a jaw for engaging the top surface of the rail 90 base at the other side of the rail; the upper edge of the body of the yoke intermediate said jaws, being formed at an angle and one leg of which bears against the bottom of the rail base when the anchor is 99 in its applied position, and the other leg of which extends downwardly from the rail base to provide clearance for the purpose described.

13. A rail anchor adapted to be driven transversely of the rail to its applied position, comprising a yoke member formed at one end with spaced jaws for engaging the top surface of a rail base at one side of a rail, and at the other end with a jaw 100 for engaging the top surface of the rail base at the other side of a rail, the upper edge of the body of the yoke intermediate said jaws being formed at an angle, the apex of which bears against the bottom of the rail base and provides an axis about 105 which said anchor rocks during its application to a rail.

14. A rail anchor adapted to be driven transversely of a rail to its applied position, comprising a yoke member formed at one end with spaced jaws for engaging the upper surface of the rail base at one side of the rail and at the other end with a jaw for engaging the top surface of the 115 rail base at the other side of the rail.

- base at the other side of the rail; the upper edge of the body of the yoke intermediate said jaws being formed at an angle, the apex of which bears against the bottom of the rail base and provides an axis about which said anchor rocks during its application to a rail, and said spaced jaws being disposed with relation to said axis whereby they are tensioned during the initial transverse movement of the yoke and subsequently relieved of a portion of said tension.
15. A rail anchor adapted to be driven transversely of the rail to its applied position, formed from a blank recessed to provide at one end a short jaw adapted to be driven into wedging engagement with one flange of a rail base and at the other end with a relatively long lug bent to provide spaced jaws for engaging the top surface of the base flange of the rail at the opposite side of the rail base; a portion of the recess beneath the spaced jaws being wider than the thickness of the rail base to facilitate the application of the anchor to a rail.
- 10 16. A rail anchor adapted to be driven transversely of the rail to its applied position, formed from a blank recessed to provide at one end a short jaw adapted to be driven into wedging engagement with one flange of a rail base and at the other end with a relatively long lug bent to provide spaced jaws for engaging the top surface of the base flange of the rail at the opposite side of the rail base; a portion of the recess beneath the spaced jaws being wider than the thickness of the rail base to facilitate the application of the anchor to a rail.
- 15 20

cess beneath the spaced jaws being wider than the thickness of the rail base to facilitate application of the anchor to a rail.

16. A rail anchor adapted to be driven transversely of the rail to its applied position, formed from a blank recessed to provide at one end a short jaw adapted to be driven into wedging engagement with one flange of a rail base and at the other end with a relatively long lug bent to provide spaced jaws for engaging the top surface of the base flange of the rail at the opposite side of the rail base; a portion of the recess beneath the spaced jaws being wider than the thickness of the rail base to facilitate the application of the anchor to a rail.
